AUTOMATIC DOFFING WINDER

Frank R. Piper and James M. Gardner, Fairfax,
Ala., assignors to West Point Manufacturing
Company, Shawmut, Ala., a corporation of Ala-
bama

Application January 2, 1951, Serial No. 203,862

2 Claims. (Cl. 242—55)

1
This invention relates to machines for winding sheet material into rolls, and particularly to apparatus for winding discrete, pre-cut lengths of material into roll package form, for convenience in handling, shipping and use. Crash towelling, for example, is commonly prepared in fifty yard lengths for use in towel roller machines, hemmed at both ends, cleaned and finished, and may conveniently and economically be supplied in roll form ready for use by means of the present invention.

It is an object of the invention, accordingly, to provide apparatus adapted to wind sheet material lengths into roll form at high speed, with a minimum of manual operation.

A primary object of the invention is to provide a simplified winding machine comprising means for automatically terminating the winding operation when the end of a material length is reached, and related means for automatically doffing finished rolls.

Another object is to provide in a winding machine means for the automatic discharge of finished rolls, and means operative on the discharge of a finished roll to automatically return the machine to condition for a succeeding winding operation.

Other objects of the invention will be in part obvious and in part pointed out hereinafter.

The invention and the novel features thereof may best be made clear from the following description and the accompanying drawings, in which:

Figure 1 is a side elevational view of an exemplary embodiment of the present invention;

Figure 2 is an end elevational view of the machine of Figure 1, looking toward the winding mandrel thereof;

Figure 3 is an enlarged sectional view taken on the line 3—3 of Figure 2, showing details of the seam detector control mechanism, and

Figure 4 is a simplified circuit diagram of the machine control system.

Referring to the drawings, the machine comprises a frame 10 supporting thereabove a curved guide plate 11. The entry end of guide plate 11 extends rearwardly to a position spaced from the machine frame, and supports at its outer end a set of guide rollers 12, one or both of which may be provided with adjustable guides 13. Intermediate its length, plate 11 may be provided with additional guides 14, and adjacent its inner end with a raised guide bar 15, mounting adjustable guides 16. Suitable frictional tensioning means, not shown, may also be provided at any suitable position along the guide plate.

2
Adjacent the inner end of the guide plate, a winding mandrel 17 is suitably end mounted, as in the frame-supported bearings 18. Mandrel 17 is desirably of square or rectangular cross-sectional shape, to facilitate doffing therefrom. Intermediate bearings 18, a driving pulley 19 is fixedly mounted on the mandrel, the pulley being engaged in driven relationship by belt 20 to the pulley 21 driven by a suitable source of power, such as electric motor 22. As shown, the motor 22 is conveniently mounted below the machine frame.

Also mounted on mandrel 17, and preferably intermediate its bearings 18, is a brake drum 23, and a pneumatic cylinder 24 is mounted on the machine frame in alignment therewith, the rod 25 of the pneumatic cylinder extending toward the brake drum and carrying at its outer end a brake shoe or similar braking element 26.

Intermediate the inner end of the guide plate and the winding mandrel are rotatably mounted rollers 27 and 28, the latter being provided with adjustable edge guides 29. Associated in operative relationship with roller 27 is a detector mechanism indicated generally as 30. As best shown in Figure 3, the detector mechanism comprises a rotatably mounted circular cam 31, provided with an edge indentation 32. A contact arm 33 extends from the cam, the outer end thereof being urged into adjacency to roller 27 by a spring 34 extending from the bracket 35, or other suitably positioned member, the movement of the contact arm being limited by stop 36. Disposed in adjacency to cam 31 is a switch 37, its arm 38 extending toward the cam and carrying at the outer end thereof a follower wheel 39, which is maintained in resilient engagement with the cam surface.

Associated with the mandrel is the pivotally mounted doffing mechanism indicated generally as 40. The doffing mechanism comprises a rigid structure 41, end mounted on shaft 42 which extends below the machine in a direction transverse to mandrel 17, the shaft being suitably supported as by bearings 43. An upwardly extending arm 44 of the doffing mechanism structure 41 carries a curved, slotted doffing plate 45, the slot 46 thereof enclosing the machine mandrel, as shown in Figure 3. A laterally extending arm 47 of the doffing structure is pivotally engaged to the rod 48 of an elongated pneumatic cylinder 49, which in turn is pivotally engaged to the machine frame. The doffing mechanism shaft 42 mounts an annular cam 50, provided with a surface indentation 51, and suitably mounted in operative relationship with cam 50 is a switch 52, its arm

53 bearing a follower wheel 54 maintained in resilient contact with the peripheral surface of the cam.

Adjacent the free end of mandrel 17 is disposed a downwardly inclined discharge chute 55, adapted to receive wound rolls doffed from the mandrel and convey them by gravity to a delivery position. Pressure air for the double acting pneumatic cylinders 24 and 49 is provided through flexible tubes 56 by a single four-way diaphragm valve 57, the operation of which is controlled by a solenoid operated three-way pilot valve 58, in conventional manner. Further elements of the control system of the machine are indicated in Figure 4, and include a starting switch 59, emergency stop switch 68, relay 61 and a double blade electromagnetic switch 62.

The operation of the mechanism will now be described in detail. Towel lengths, suitably finished and in folded or similar form, may be positioned beneath the outer end of the guide plate on a suitable platform, in a basket or by other means. As the initial step of a winding operation, one end of a towel length is manually threaded through the machine and engaged to the mandrel. In the example shown, the towel end is passed around the guide rollers 12, stretched over and along guide plate 11, and then conducted below and around roller 21, the detector arm 33 being momentarily displaced for this purpose. The towel end is then threaded above and around roller 28 and led to the winding mandrel 17, as shown in Figure 3. To engage the towel end to the mandrel, the latter may be rotated a revolution or two, conveniently by employing brake drum 23 as a hand wheel. This completes the threading of the machine, in the course of which due attention is given to the various pairs of edge guides. The machine is so constructed, as will be evident, as to facilitate the threading operation, which may be performed very quickly by a practiced operator.

The towel length having been threaded in the machine, the winding operation may be initiated by momentarily closing starting switch 59, which may be mounted at any convenient location on or adjacent the machine. As will be seen in Figure 4, momentary closing of switch 59 completes a circuit through the solenoid of relay 61, whereupon the relay switch closes, thereby completing a circuit through motor 22, which starts and drives mandrel 17, whereby the towel length is pulled through the apparatus and wound tightly and evenly upon the mandrel. Because the material length is firmly controlled, the mandrel may be driven at high speed, and the time consumed by the winding operation correspondingly reduced to a minimum. Closing of the relay switch 61 also completes a holding circuit for the relay solenoid, this circuit including the closed relay, the left-hand blade of normally open switch 62, and the normally closed switch 69, so that the motor continues to run when the button switch opens after its momentary closing.

In the course of normal operation, motor 22 continues to operate and wind the towel length on the mandrel, until the trailing end of the towel length reaches roller 21. The trailing end being hemmed, the thickened portion thereof will strike detector arm 33, which rides the towel length in the course of its passage over roller 21, and displaces the arm whereby cam 31 is rotated correspondingly in the clockwise direction as viewed in Figure 3. This movement of the detector cam displaces follower wheel 39 of switch arm 38 from

the cam indentation 32 to the outer peripheral surface of the cam, whereby the normally open switch 37 is momentarily closed.

The momentary closing of switch 37 by the end of the towel length initiates several operations. Referring again to the circuit diagram, it will be seen that momentary closing of this switch completes a circuit through the solenoid of electromagnetic switch 62, closing that switch. Closing of switch 62 completes a holding circuit through its solenoid whereby the switch is locked in, the holding circuit being completed through switch 52 associated with the doffing mechanism shaft 42, and the right-hand blade of closed switch 62.

Closing of switch 62 also breaks the holding circuit through the solenoid of relay 61, which thereupon opens, breaking the circuit through motor 22, whereby the motor is deenergized. The closing of switch 62 also completes a circuit including switch 52 and closed switch 62, through the solenoid of pilot valve 58, whereby the pilot valve is energized and functions to reverse the four-way diaphragm valve 57. Pilot valve 57 is thereupon operative to effect extension of pneumatic cylinder 24 and retraction of pneumatic cylinder 49. Extension of the rod of pneumatic cylinder 24 causes frictional engagement of brake shoe 26 with the mandrel brake drum 23, whereby the mandrel and the completely wound roll thereon are brought to a complete stop. Substantially simultaneously, retraction of the rod of cylinder 49 effects pivotally swinging movement of the doffing mechanism about the axis of shaft 42, whereby the doffing plate 45 traverses the length of the mandrel in the direction of the free end thereof, engaging the adjacent end of the wound roll and doffing it therefrom.

The doffed roll falls into the inclined discharge chute 55 and rolls downwardly thereon, to a suitable delivery position. The inclination of the discharge chute is desirably such as to cause the finished rolls to roll therealong in the winding direction, to avoid unwinding in the chute. At the delivery point, the wound rolls may accumulate and be removed at convenient intervals, for tying, wrapping or the like.

Passage of the sheet material end past the detector mechanism, then, is effective to deactivate the mandrel drive, actuate the mandrel brake means, and initiate operation of the doffing mechanism. While these operations take place substantially simultaneously, it will be evident that some travel of the cloth length occurs before the mandrel is brought to a complete stop. In the exemplary embodiment, this time lag is adequate to permit movement of the trailing material end from roller 21 to the roll on the mandrel, whereby the winding is completed. Similarly, a slight time lag in operation of the doffing mechanism is inherent, and this is taken advantage of to insure that the winding operation is completed and the mandrel brought to full stop before the end of the wound roll is engaged by doffing plate 45. The spacing between the initial position of the doffing plate and the cloth roll may be varied to effect contact of the cloth roll by the doffing plate at the instant the doffing roll stops, or substantially immediately thereafter.

Although the detector mechanism is conveniently mounted in operative association with roller 21 in the exemplary embodiment, it will be apparent that it may be otherwise positioned. For example, its arm may ride the cloth length at a point closer to or further from the mandrel,

the time lag due to braking of the mandrel being correspondingly adjusted to allow for passage of the trailing material end from the detector mechanism to the mandrel, after tripping of the detector mechanism and before the mandrel stops. Similarly, it will be apparent that detector mechanism other than that specifically disclosed may be employed. For example, if the material length be not provided with end hemps, the mechanism may detect the end thereof by making a circuit through the material supporting member therebeneath, when the end has passed therebetween. Other conventional and equivalent detector mechanisms will readily occur to those skilled in the art.

At the end of the doffing mechanism stroke, the cam 50 will rotate with shaft 42 sufficiently to bring its indentation 51 into alignment with the follower wheel 54 of switch arm 53, whereupon the follower wheel will drop into the indentation, displacing the switch arm and permitting the switch to open.

Opening of switch 52 at this phase of the cycle, as will be seen in Figure 4, is effective to break the circuits through the solenoid of switch 62 and through the solenoid of pilot valve 58, whereby the switch 62 opens and the solenoid of valve 58 is deenergized. Valve 58 thereupon effects reversal of the four-way diaphragm valve 57, which then functions to effect retraction of cylinder 24 and extension of cylinder 49. The extension of cylinder 49 returns the doffing mechanism to initial position shown in Figure 2, and the retraction of solenoid 24 frees mandrel 17 for the ensuing winding operation. Arrival of the doffing mechanism at the end of its operative stroke, then, is effective to automatically reverse the doffing mechanism and return it to initial position, and to release the mandrel brake.

Threading of the succeeding material length through the machine for winding may be substantially completed during the doffing of the preceding roll and the return stroke of the doffing mechanism. Freeing of the mandrel brake permits the new towel end to be engaged to the 45 mandrel in the manner previously described, whereupon the next winding operation may be initiated by momentary closing of switch 59.

In the event switch 37 fails to function, that is, if switch 37 is not momentarily closed by the final 50 end of a towel length moving therewith, the winding operation may be terminated and the braking and doffing mechanisms activated by means of the stop switch 60. Stop switch 60 is of double-throw push button type, normally occupying the position shown in circuit with the solenoid of relay 61, and may be displaced momentarily to break the circuit through the solenoid of relay 61, and to close a circuit through the 55 solenoid of switch 62 and a circuit through the solenoid of pilot valve 58. In other words, dis-

placement of switch 60 performs the same function as does momentary closing of switch 37, and an identical sequence of operations follows. The stop switch 60 may be utilized to stop the winding operation, brake the mandrel and activate the doffing mechanism at any time. If desired, the stop switch or another switch may be utilized merely to deenergize motor 22, or to deenergize the motor and brake the mandrel.

It will thus be seen that there has been provided by this invention a structure in which the various objects hereinbefore set forth, together with many practical advantages, are successfully achieved. As various possible embodiments may be made of the mechanical features of the above invention, all without departing from the scope thereof, it is to be understood that all matter hereinbefore set forth or shown in the accompanying drawings is to be interpreted as illustrative, and not in a limiting sense.

We claim:

1. Apparatus for winding and automatically doffing discrete lengths of sheet material comprising a mandrel mounted at one end and free at the other end thereof, power means for driving said mandrel, manually operable means for initially actuating said mandrel driving means, means for braking said mandrel, doffing means associated with said mandrel and adapted to traverse from the mounted end to the free end of the mandrel, and remove finished rolls therefrom, means responsive to passage of the trailing sheet material end past a point adjacent said mandrel to simultaneously deactivate said mandrel driving means, actuate said mandrel braking means, and actuate said mandrel doffing means, and means effective at the end of the doffing means stroke to simultaneously reverse said doffing means and deactivate said mandrel braking means, whereby said mandrel may be manually rotated to engage a successive sheet material length thereto.

2. Apparatus according to claim 1, including a discharge chute disposed and adapted to receive finished rolls doffed from said mandrel, said chute being inclined relatively to the horizontal so that finished rolls will roll therealong away from said mandrel in the winding direction of said rolls.
